UNITED STATES PATENT OFFICE

JOHN C. BLACK, OF LOS ANGELES, CALIFORNIA, ASSIGNOR, BY MESNE ASSIGNMENTS, TO RICHLFIELD OIL COMPANY OF CALIFORNIA, OF LOS ANGELES, CALIFORNIA, A CORPORATION OF DELAWARE

PROCESS OF PURIFYING HYDROCARBONS

Application filed, March 10, 1928. Serial No. 260,653.

This invention relates to the purification of hydrocarbons, and while not necessarily confined thereto, it more specifically refers to the treatment of naphtha or gasoline stock synthetically produced by the cracking of hydrocarbon oils, such as petroleum or shale oil, or distillates derived from relatively high sulphur-bearing crude oils in which hydrogen sulphide, mercaptans and other sulphur-bearing hydrocarbons, as well as varying percentages of unstable hydrocarbons, such as diolefines, may be present, or formed during said distillation or cracking operation.

This invention is particularly applicable for refining gasoline stock made according to United States Patent No. 1,426,813 granted to me April 22, 1922.

One of the principal objects of this invention is to accomplish a partial desulphurizing and purification of gasoline or naphtha stock by a sequence of operations involving first treating crude gasoline, which may or may not have had a preliminary sulphuric acid treatment, with caustic soda, depending upon the quality of the stock to be purified and the extent of the purification desired, followed by a treatment under pressure with an oxidizing agent in the presence of a water solution of caustic soda, a subsequent treatment with an adsorbent clay at an elevated temperature under pressure, and a final distillation.

Another object of this invention is to provide a continuous system or batch process for purifying gasoline stock produced by cracking petroleum oils to remove therefrom the unstable hydrocarbons either before or after a "sweetening" operation, or other refining operations known in the art, by a treatment with an adsorbent clay under pressure and at elevated temperatures sufficient to polymerize all the unstable hydrocarbons contained therein, with the formation of higher boiling oils and then separating the purified gasoline stock from the higher boiling polymerized hydrocarbons, by distillation.

With the foregoing preliminary explanation, the preferred embodiment of this invention will now be more fully explained by reference to the accompanying drawing which is a diagrammatical representation of an ap-

paratus in which the invention may be carried out.

In the drawing, 1 indicates generally a gasoline supply tank containing the stock to be treated, to which is connected near the top, a pipe 2 controlled by a valve 3 and leads to a source of supply not shown. A pipe 4 controlled by a valve 5 connects the crude gasoline tank 1 to the suction side of a pump 6. A pipe 7 connects the discharge side of pump 6 to a mixer 8. The mixer 8 may be of any well-known type such as a jet mixer or a container provided with baffle plates. A pipe 16 connects the mixer 8 to a separator 17. 13 indicates generally a caustic soda supply tank which is connected to the suction side of a pump 10 by a pipe 11 controlled by the valve 12. A pipe 14 controlled by the valve 15 is connected to the caustic tank 13 near the top and leads to a source of supply not shown. A pipe 9 connects the discharge side of the pump 10 to the bottom of the mixer 8. A pipe 22 connects the separator 17 to heat exchanger 23. A pipe 27 connects the heat exchanger 23 to a heater 26. The heater 26 is provided with a steam inlet pipe 24 controlled by a valve 25. 31 indicates the steam outlet pipe controlled by the valve 32. The steam supply pipe 24 leads to a source of steam not shown and the steam outlet pipe 31 leads to a source for waste steam not shown. A pipe 28 connects the heater 26 to a mixer 29. 37 indicates generally a supply tank for holding a suspension of manganese dioxide in a water solution of caustic soda. The tank 37 is provided with a stirrer 38 which is operated by a motor 39 which is connected to the stirrer 38 by means of gears as shown. A pipe 40 controlled by the valve 41 is connected to tank 38 near the top and leads to a source of supply not shown. A pipe 35 controlled by the valve 36 connects supply tank 37 near the bottom to the suction side of pump 34. A pipe 33 connects the discharge side of pump 34 to the bottom of mixer 29. The mixer 29 may be any mixer known in the art for mixing solutions containing a suspended comminuted solid such as a jet mixer or a mixer provided with baffle plates. A pipe 30 connects the mixer 29 to a treater 65 end-100

ing in a spray line. The pipe 66 connects the treater 65 near the bottom to a separator 67. A pipe 68 connects the separator 67 to the suction side of a pump 75, the flow from which is controlled by the valve 74. A pipe 69 controlled by the valve 70 connects the separator 67 at the bottom to the spent manganese dioxide caustic soda tank 71. A pipe 73 controlled by the valve 72 is connected to the tank 71 near the bottom and leads to a source of storage or recovery plant not shown. A pipe 78 controlled by the valve 79 connects the discharge side of pump 75 to clay treater 80. A pipe 83 controlled by the valve 84 connects the pipe 78 to clay separator tank 85. A pipe 76 controlled by the valve 77 connects the clay treater 80 at the bottom to the suction side of pump 75. A conveyor 81 connects the clay bin 82 to clay mixer 131 at the top by means of which desired amounts of an adsorbent clay may be introduced into the said clay mixer 131. The pipes 86 and 126 controlled by valve 127 connect the clay separator 85 to a cooling coil 128. Cooling coil 128 is contained in the cooler box 129. Pipe 130 connects the cooler coil 128 to the clay mixer 131. The clay mixer is provided with a stirrer 132 by means of which the introduced adsorbent agent and introduced gasoline may be kept in a commingled state. Pipe 134 controlled by valve 133 connects the clay mixer 131 at the bottom to the suction side of pump 135. Pipe 136 controlled by valve 137 connects the discharge side of pump 135 to clay treater 80.

The pipe 86 is connected by a branch pipe to the suction side of pump 88, the flow being controlled by valve 87. A pipe 89 controlled by the valve 90 connects the discharge side of the pump 88 to heat exchanger 23. A pipe 42 controlled by the valve 43 connects the heat exchanger 23 to pipe 52. The pipe 52 controlled by the valve 53 connects the treated gasoline storage tank 51 to the suction side of pump 54. A pipe 44 controlled by the valve 45 connects the pipe 43 to cooler 46. A pipe 47 controlled by a valve 48 connects the cooler 46 to pipe 91. The pipe 91 controlled by the valve 92 connects the treated gasoline tank 51 to a cooler 94. A pipe 49 controlled by a valve 50 is connected to the cooler 46 and leads to a source of cooling water not shown. A pipe 200 controlled by the valve 201 is connected to the cooler 46 and leads to a source of waste not shown. A pipe 55 controlled by the valve 56 connects the pump 54 on the discharge side to a heater 59. A pipe 60 controlled by the valve 61 is connected to the heater 59 and leads to a source of steam not shown. A pipe 62 controlled by a valve 63 is connected to the heater 59 and leads to a source of waste steam not shown. A pipe 57 controlled by a valve 58 connects the heater 59 to a fractionating tower 64. A steam pipe 111 controlled by valve 112 is connected to

fractionating tower 64 near the bottom and leads to a source of steam not shown. A pipe 125 connects the fractionating tower 64 at the top to a condenser pipe 104. The condenser pipe 104 is contained in the condenser box 105. A pipe 106 connects the condenser pipe 104 to a finished gasoline tank 108. The valve 107 controls the flow of gasoline coming through the pipe 106. A pipe 102 controlled by the valve 103 connects the clay separator 85 at the bottom to the suction side of a pump 101. A pipe 99 controlled by the valve 100 connects the discharge side of pump 101 to a filter press 97. The filter press 97 is provided with filter plates 98. The pipe 95 controlled by the valve 96 connects the filter press 97 to the cooler 94. A pipe 205 controlled by the valve 204 is connected to the cooler 94 and leads to a source of cooling water not shown. A pipe 203 controlled by the valve 202 is connected to the cooler 94 and leads to a source of waste not shown. The pipe 91 controlled by the valve 93 connects the cooler 94 to treated gasoline tank 51. The pipe 113 controlled by the valve 114 connects the fractionating tower 64 at the bottom to cooler 115. The pipe 121 controlled by valve 122 connects the cooler 115 to a source of cooling water not shown. The pipe 123 controlled by the valve 124 is connected to the cooler 115 and leads to a source of waste not shown. A pipe 116 controlled by the valve 117 connects the cooler 115 to heavy oil tank 118. The heavy oil tank 118 is provided with an outlet pipe 119 controlled by valve 120. The finished gasoline tank 108 is provided with an outlet pipe 109 controlled by valve 110 and leads to a source of gasoline storage not shown. A pipe 18 controlled by the valve 19 connects the separator tank 17 at the bottom to spent caustic tank 20. The spent caustic tank 20 is provided with an outlet pipe 21 controlled by a valve 22^a and leads to a source of caustic recovery not shown.

The preferred process as carried out in the apparatus just described is as follows:

The crude gasoline storage tank 1 is filled with the stock to be treated from the pipe 2. The pipe 2, controlled by the valve 3, leads to a source of crude gasoline not shown. Crude gasoline or naphtha stock contained in the tank 1 which may or may not have had a preliminary treatment with sulphuric acid, is continuously discharged by the pump 6 into the mixer 8, passing through the pipes 4 and 7, the rate of flow being regulated by operating valve 5. At the same time a regulated stream of a water solution of caustic soda is commingled with the gasoline stock entering the mixer 8, by operating pump 10. Pump 10 takes suction on the caustic tank 13 through the pipe 11 and discharges through the pipe 9, the flow of caustic solution being regulated by operating valve 12. The strength and quantity of the water solu-

tion of caustic soda which is commingled with the gasoline stock entering the mixer 8 depends upon the stock under treatment. As an example, I may use a strength of caustic soda solution varying from as low as 6 degrees Bé. to as high as 50 degrees Bé., and the quantity employed may range from as low as 1 per cent by volume to as high as 25 per cent by volume. The treatment of the crude gasoline stock with caustic soda removes substantially all of the hydrogen sulphide and certain percentages of the mercaptans from the gasoline stock. The commingled gasoline stock and caustic soda solution passed from the top of the mixer 8 through the pipe 16 and into the separator 17 where the caustic soda solution containing substantially all of the hydrogen sulphide in the form of sodium sulphide and a certain portion of the mercaptans in solution, are separated from the gasoline stock by regulating valve 19 which permits the separated spent caustic solution to pass through the pipe 18 and into the tank 20. From the separator 17 the caustic treated gasoline stock passes through the heat exchanger 23 and heater 26 where a temperature of the desired degree is attained, preferably 250 to 400 degrees F., this degree of temperature being governed by regulating valve 25 of the entrance steam pipe 24, the exhaust steam passing to a source not shown through the pipe 31, controlled by the valve 32. From the heater 26 the hot gasoline stock passes through the pipe 28 and into mixer 29 where it is commingled under pressure with a water solution of caustic soda containing suspended manganese dioxide. The amount of caustic soda solution containing suspended manganese dioxide employed in this operation, may range from as low as 1 per cent to as high as 10 per cent or a little higher by volume of a 6 to 50 degree Bé. caustic soda water solution, containing 1 to as high as 10 per cent or a little more by weight, comminuted manganese dioxide. By this treatment with a water solution of caustic soda containing suspended manganese dioxide, the mercaptans and any other corrosive sulphur compounds are converted into non-corrosive compounds, thereby rendering the gasoline stock "sweet" to the "doctor test." By means of the pipe 40 which leads to a source not shown, controlled by the valve 41, the tank 37 is filled with a water solution of caustic soda of the desired strength, containing the requisite quantity of manganese dioxide. The manganese dioxide contained in the caustic soda solution in tank 37 is kept in a suspended state by the stirrer 38 which is operated by motor 39. From the tank 37 the caustic soda water solution containing the suspended manganese dioxide passes through pipe 35 and into the suction side of pump 34 which discharges the same through pipe 33 and into the mixer 29, the rate of flow being governed by valve 36. From the mixer 29 the commingled gasoline stock and caustic soda solution containing the suspended manganese dioxide, passes through treater 65, pipe 66 and into separator 67 where the used caustic soda solution and manganese dioxide are separated from the treated gasoline stock and conducted to a tank 71 passing through the pipe 69 controlled by the valve 70. The spent caustic soda solution containing manganese dioxide is conducted to a recovery plant not shown passing out through the pipe 73 controlled by the valve 72. The treated gasoline stock now substantially free of corrosive sulphur compounds and "sweet" to the "doctor test", passes from separator 67 through the pipe 68 and into the suction side of pump 75, the flow being controlled by valve 74. Pump 75 discharges the gasoline stock through the pipe 78 into the clay treater 80, the flow being regulated by valve 79. In clay treater 80 the heated gasoline stock under its own vapor pressure, which is approximately 100 to 300 pounds, and at a temperature ranging from 200 to 400 degrees F., is commingled with the required amount of an adsorbent agent such as a comminuted hydrous magnesium silicate, an aluminum silicate, or an acid treated clay, the latter of which may be produced according to the method employed in my United States Patent 1,656,997, Process of refining oil, patented January 24, 1928. The amount of adsorbent agent employed ranges from 1/2 of one per cent to as high as 10 per cent by weight, depending upon the stock to be treated and the product desired. The adsorbent agent not only adsorbs certain impurities from the gasoline stock, but also acts as a polymerizing agent, thereby effecting a relatively rapid polymerization of the unstable hydrocarbons such as the diolefines, and other unstable hydrocarbons which if allowed to remain in the gasoline stock on standing in storage, would slowly condense with the formation of undesired gasoline soluble colored constituents, the removal of which would be necessary in order to obtain a water white gasoline stock, thereby incurring an additional expense and loss of the gasoline stock. The clay treater 80 is so arranged that a circulating agitation may be effected, and the gasoline stock continuously commingled with clay and continuously withdrawn into the clay separator 85. This is accomplished by proper regulation of valves 77, 84, 79 and 74. A comminuted adsorbent agent, contained in the hopper 82, is continuously introduced into the clay mixer 131 by operation of the elevator 81. At the same time a small quantity of the treated gasoline or naphtha from the clay separator 85 is continuously introduced into the clay mixer 131 and commingled with the introduced adsorbent agent by the operation of stirrer 132. The quantity of treated gasoline

- or naphtha introduced is just sufficient to obtain a pumpable mixture. The gasoline introduced into clay treater 131 from clay separator 85 passes through the pipes 86 and 126, cooling coil 128 and pipe 130. The gasoline is cooled below its vaporizing temperature during the passage through cooling coil 128. From the clay mixer 131 the commingled adsorbent agent and gasoline passes through the pipe 134, controlled by valve 133, and into the suction side of pump 135 which discharges the same through the pipe 136, controlled by the valve 137 and into the clay treater 80.
- 15 The commingled gasoline stock and adsorbent agent in clay treater 80 is continuously discharged through the pipe 83 and into the clay separator 85 by regulating valve 84. In the clay separator 85 the adsorbent agent separates from the gasoline stock and is drawn off together with a small percentage of the gasoline stock passing through the pipe 102, the flow of which is regulated by valve 103. From the pipe 102, the adsorbent 20 agent containing a small percentage of the gasoline stock passes into the suction side of pump 101 which discharges the same through the pipe 99, controlled by the valve 100 and into the filter press 97, where the major portion of the gasoline stock contained by the adsorbent agent is separated, the adsorbent agent collecting on the filter plates 98 and the gasoline stock passing through the pipe 95, controlled by the valve 96. From 25 the pipe 95 the separated gasoline stock passes through the cooler 94 which is provided with a water inlet pipe 205 controlled by valve 204 and a water outlet pipe 203 controlled by valve 202, by means of which the separated 30 gasoline stock is cooled to the desired degree. From the cooler 94, the cool gasoline stock separated from the agent passes through the pipe 91 controlled by the valve 92 and into the storage tank 51.
- 35 The pipe 95 the treated gasoline stock as it separates from the adsorbent agent in clay treater 85 passes through pipe 86 and into the suction side of pump 88, the flow of which is controlled by valve 87. The pump 88 discharges 40 the hot treated gasoline stock through the pipe 89, controlled by the valve 90, and through the heat exchanger 23 where the said hot treated gasoline stock undergoes a heat exchange with the incoming oil to be treated.
- 45 From the heat exchanger 23 the partly cooled gasoline stock passes through pipe 42 and into the suction side of pump 54, or the partly cooled gasoline stock may be caused to pass through the cooler 46 and then into the storage tank 51, in which case valve 43 is closed, and valve 45 is open, permitting the treated stock to pass through pipe 44, cooler 46, pipe 47 and into pipe 91 which is connected to storage tank 51, valve 48 being open. The pump 50 54 discharges the treated gasoline stock com-
- ing from the storage tank 51 through the pipe 55, controlled by the valve 56, or the treated gasoline stock coming through the pipe 42 may be directly introduced into the suction side of pump 54 without passing through the cooler 46 and thereafter discharged through the pipe 55 and into the heater 59. Preferably the partly cooled gasoline stock is not passed through the cooler 46 but is directly permitted to flow into the suction side of the pump 54 whereby conservation of heat is effected in the distillation operation to follow. The gasoline stock passes from the pipe 55 through the heater 59, pipe 57 and into the fractionating tower 64 where the gasoline boiling point stock is separated from the higher boiling hydrocarbons and polymerized products produced in the treatment. In order to facilitate the distillation operation, steam is introduced into the fractionating tower 64 coming from a source not shown through the pipe 111 controlled by the valve 112. The vaporized purified gasoline stock and introduced steam pass from the fractionating tower 64 through the pipe 125 and are condensed during the passage through the condenser coil 104. The condensed purified gasoline stock and water pass from the condenser coil 104 through the pipe 106 and into the finished gasoline tank 108, the flow being regulated by valve 107. The finished gasoline tank 108 is provided with pipe 109 controlled by valve 110 which leads to a storage tank not shown.
- 55 While the foregoing described process is well adapted for carrying out the objects of the present invention, it is to be understood that various other oxidizing agents known in the art may be employed in place of manganese dioxide for rendering gasoline "sweet" to the "doctor test," such as hypochlorite of soda, copper oxide, iron oxide, per-sulphates, and the like, and thereafter treated with an adsorbent agent of the class described at 60 temperatures and pressure sufficient to polymerize the unstable unsaturated hydrocarbons by the method herein described and thereafter separated from the treated gasoline or naphtha stock by fractionation. Also it is to be understood that the crude gasoline or naphtha stock may be first treated with an adsorbent agent at the temperatures and pressures described in the preferred process and thereafter treated with sulphuric acid, caustic soda, and an oxidizing agent to render the gasoline or naphtha stock "sweet" to the "doctor test" or by other processes well-known in the art, and that various other changes and modifications may be made without departing 65 from the spirit of the invention and the invention includes all such changes and modifications as appear within the scope of the appended claims.
- 70 What I claim is:
- 75 1. A process of treating gasoline or naph-

tha derived from cracking petroleum oils, comprising commingling the gasoline or naphtha stock which has been treated with sulphuric acid, caustic soda and rendered "sweet" to the "doctor test" by treatment with a water solution of caustic soda containing the requisite quantity of suspended manganese dioxide, with a comminuted adsorbent clay at an elevated temperature sufficient to polymerize substantially all the unstable hydrocarbons contained therein and under a pressure sufficient to prevent any substantial vaporization of the gasoline or naphtha and then separating the gasoline or naphtha from the products of polymerization, by distillation.

2. A process of treating gasoline or naphtha derived from cracking petroleum oils comprising, continuously commingling the gasoline or naphtha with a water solution of caustic soda, continuously separating the water solution of caustic soda containing dissolved impurities from the gasoline or naphtha, continuously passing the caustic treated gasoline or naphtha in heat exchange relationship with hot gasoline or naphtha subsequently produced, and further heating the said caustic treated gasoline or naphtha to a temperature of substantially not less than 250 degrees F., continuously commingling the said heated gasoline or naphtha with a water solution of caustic soda containing suspended manganese dioxide in quantities sufficient to render the gasoline or naphtha "sweet" to the "doctor test," continuously separating the heated gasoline or naphtha from the water solution of caustic soda and suspended manganese dioxide, continuously commingling the said separated heated gasoline or naphtha with a comminuted adsorbent clay at a pressure sufficient to prevent any substantial vaporization of the gasoline or naphtha for a period of time sufficient to polymerize substantially all of the unstable hydrocarbons contained therein, and then separating the purified gasoline or naphtha from the higher boiling oils and products of polymerization, by distillation.

3. A process of treating gasoline or naphtha derived from cracking petroleum oil comprising, commingling the gasoline or naphtha with a water solution of caustic soda containing suspended manganese dioxide at an elevated temperature and for a period of time sufficient to render the gasoline "sweet" to the "doctor test," separating the gasoline or naphtha from the water solution of caustic soda and suspended manganese dioxide and then commingling the separated gasoline or naphtha with a comminuted adsorbent clay at a temperature of substantially not less than 250 degrees F., under a pressure sufficient to prevent vaporization of the gasoline or naphtha and for a period of time sufficient to effect polymerization of substantially all of

the unstable hydrocarbons contained therein, and finally separating the purified gasoline or naphtha from higher boiling oils and products of polymerization.

In testimony whereof I affix my signature. ⁷⁰
